UNITED STATES PATENT OFFICE.

WILLIAM JOSEPH MIMS, OF ASHVILLE, ALABAMA.

MECHANISM FOR CHURNS.

1,173,013.

Specification of Letters Patent. Patented Feb. 22, 1916.

Application filed January 28, 1914. Serial No. 815,068.

To all whom it may concern:

Be it known that I, WILLIAM J. MIMS, a citizen of the United States, residing at Ashville, in the county of St. Clair and State of Alabama, have invented new and useful Improvements in Mechanisms for Churns, of which the following is a specification.

This invention relates to mechanism for churns and it consists in the novel features hereinafter described and claimed.

An object of the invention is to provide a mechanism of simple structural arrangement adapted to be easily and quickly applied to the edge of a table or bench and which may be connected with the churn dasher rod, the parts being so arranged that when the mechanism is operated the dasher is caused to reciprocate in the churn body.

With the above objects in view the mechanism comprises a standard provided with an opening and having at its lower end legs adapted to rest upon the upper surface of the top of the table or bench. The said standard is further provided with a brace 4 which is located between the said legs. The standard is further provided with an arm which is adapted to extend under the top of the table or bench and the said arm carries a set screw adapted to be clamped against the under side of the top of a table or bench. The standard is further provided with guides in which is slidably mounted a rod having means adapted to be adjustably connected with the dasher rod. A crank shaft 13 is journaled for rotation at the upper portion of the standard and a pitman 14 is pivotally connected at one end with the crank of the shaft 13 and at its other end is pivotally connected with the upper end of the rod 8. A crank shaft 15 is journaled for rotation at the intermediate portion of the standard 1 and is provided with a handle 16. A relatively large gear wheel 17 is mounted upon the intermediate portion of the shaft 15 and is located in the opening 2 in the standard 1 and meshes with a relatively small gear wheel 18 mounted upon the crank shaft 13.

In the accompanying drawing:—Figure 1 is a side elevation of the mechanism. Figs. 2 and 3 are detailed views of the features thereof.

The churning mechanism comprises a standard 1 which is provided at its upper portion with an opening 2. The said standard is further provided at its lower end with spaced legs 3 which are adapted to rest upon the upper surface of the top of a table or bench. The said standard is further pro-

vided with a brace 4 the lower end of which is also adapted to rest upon the upper surface of the top of the table or bench and the brace 4 is positioned between the legs 3. 60

The standard 1 is further provided at its lower portion with an arm 5 which is adapted to extend around and under the edge of the top of the table or bench. The arm 5 is provided at its lower end with a screw 6 65 adapted to be engaged with the under side of the top of the table or bench whereby the said standard is held in position upon the said top. The screw 6 is located in a vertical plane which lies between the lower ends of the legs 3 and the brace 4, consequently when the said screw is engaged with the under side of the top of a table or bench the standard 1 is firmly held in position thereon. The standard 1 is further provided with two guides 7 75 said guides being spaced from each other. A rod 8 is slidably mounted in the guide 7 and is provided in the vicinity of its lower end with three eyes 9. The intermediate eye 9 is provided with a clamp screw 10. The 80 eyes 9 are adapted to receive the upper portion of a dasher rod 11 and by tightening the screw 10 the said rod 11 is secured at an adjusted position with relation to the rod 8. The dasher rod 11 passes through the top of a churn 12 which is adapted to be positioned upon the same floor or level upon which the table or bench stands.

A crank shaft 13 is journaled for rotation at the upper portion of the standard 1 and a 90 pitman 14 is pivotally connected at one end with the crank of the shaft 13 and at its other end is pivotally connected with the upper end of the rod 8. A crank shaft 15 is journaled for rotation at the intermediate portion of the standard 1 and is provided with a handle 16. A relatively large gear wheel 17 is mounted upon the intermediate portion of the shaft 15 and is located in the opening 2 in the standard 1 and meshes 100 with a relatively small gear wheel 18 mounted upon the crank shaft 13.

From the above description taken in conjunction with the accompanying drawing it will be seen that when the standard 1 is 105 mounted upon a table as described and the dasher rod 11 of a churn is connected with the rod 8 and as the shaft 15 is rotated the rotary movement is transmitted through the intermeshing gear wheels 17 and 18 to the 110 shaft 13. As the crank of the shaft 13 rotates about the axis thereof the pitman 14

is moved longitudinally which in turn moves the rod 8 through the guides 7 and the dasher rod 11 is reciprocated with relation to the churn 12.

5 Furthermore it will be seen that the mechanism is of simple structural arrangement and that the standard 1 is poised upon the legs 2 and brace 4 so that it is firmly supported upon the table or bench and by reason 10 of the peculiar position of the arm 5 the said standard is rigidly held in such position when the screw 6 is tightened.

Having described the invention what is claimed is:—

15 A churn mechanism comprising a standard provided with an opening and having at its lower end and at one side spaced legs, said standard further having at its lower end a laterally disposed brace which is positioned opposite the space between the legs, the lower ends of the legs and the brace lying in the same plane, the standard further having at its lower end and at its other side an arm extending below the lower end 25 of the legs and brace, a clamping screw car-

ried by the arm and positioned between the lower ends of the legs and brace, said standard having at its last mentioned side spaced guides, a rod slidably mounted in the guides, means carried by the rod for connecting the same with a dasher rod, a crank shaft journaled upon the standard and operatively connected with the first mentioned rod, a second crank shaft also journaled upon the standard, an intermeshing gear wheel mounted upon said shafts and located in the opening between the opposite sides of the standard, there being connections between the legs and side of the standard having the guide, said connections being located below 40 the gear wheels and connecting the legs with the opposite side of the standard at points between the guides.

In testimony whereof I affix my signature in presence of two witnesses.

WILLIAM JOSEPH MIMS.
